(57) **CLAIM**

The ornamental design for a cold therapy treatment device as shown and described.

DESCRIPTION

FIG. 1 is a perspective view of a cold therapy treatment device showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is a bottom plan view thereof;

FIG. 9 is an enlarged view of portion of FIG. 1;

FIG. 10 is an enlarged view of portion of FIG. 1;

FIG. 11 is an enlarged view of portion of FIG. 2; and,

FIG. 12 is an enlarged view of portion of FIG. 2.

The broken lines in the drawings illustrate portions of the cold therapy treatment device that form no part of the claimed design.

1 Claim, 12 Drawing Sheets
